Taft.

UNITED STATES PATENT OFFICE.

SYDNEY E. TAFT, OF FRAMINGHAM, MASSACHUSETTS, ASSIGNOR TO SPARTAN NEEDLE COMPANY, OF PROVIDENCE, RHODE ISLAND, A CORPORATION OF RHODE ISLAND.

KNITTING NEEDLE.

Application filed January 29, 1920. Serial No. 354,764.

To all whom it may concern:

Be it known that I, SYDNEY E. TAFT, a citizen of the United States, and a resident of Framingham, in the county of Middlesex and State of Massachusetts, have invented an Improvement in Knitting Needles, of which the following description, in connection with the accompanying drawings, is a specification, like characters on the drawings representing like parts.

This invention relates to knitting instruments and more particularly to that type of instruments wherein the yarn drawing and loop shedding members have independent movements.

The invention consists of the combination and arrangement of parts set forth in the following specification and particularly pointed out in the claims and in the accompanying drawings I have shown merely for illustrative purposes a single embodiment of the invention wherein:

Fig. 1 is a side elevation of the instrument somewhat enlarged;

25 Figs. 2 to 6 inclusive are detail views somewhat enlarged illustrating the operative ends of the yarn drawing member and sheath in various positions occupied thereby during the loop forming operations;

30 Fig. 7 is a detail perspective view of the upper end of the sheath member;

Fig. 8 is a front elevation of the same, and

Fig. 9 is a transverse section taken substantially on the line 9—9 of Fig. 2.

35 In the drawings 1 is the knitting instrument consisting of a yarn drawing member 2 having at its upper end a suitable hook 3 for engaging the new yarn during the knitting operation and drawing said new yarn through a previously formed loop that is being supported upon the shank of said yarn drawing member in the usual well known manner.

The hook embodying this invention may be constructed in various forms but herein I have provided a hook having a relatively long beard 4 which may or may not be resilient; herein, however, the said beard is shown as relatively nonresilient although it

50 is slightly rounded upon its front edge and tapered substantially from the bend or head to its extremity where it preferably terminates in a point 5. It is desirable for reasons hereinafter explained that the taper of said beard be confined to the outer edge

thereof and furthermore that the degree of said taper be increased rather abruptly at the portion 6 near the point 5.

The material composing the hook 3 of the yarn drawing member is considerably reduced in thickness, or extenuated so as to produce a hook, the bend whereof will be large enough to allow the yarn to freely reeve therethrough and yet retain the outside dimension of said bend at least substantially 65 within the dimension of the shank or stem 8 from its front to its rear edges. The reducing of the end of said member 2 results in the formation of the neck 7 which tapers gradually from the large to the smaller dimension and thereby produces an inclined edge 9 a short distance beneath the point 5 of said beard.

A butt 10 is provided upon the shank 8 of said yarn drawing member and constitutes 75 means whereby said member may be functioned during knitting. The yarn drawing member 2 is further provided with a groove 11 extending longitudinally of a portion of one side of its shank, as shown in dotted 80 lines Fig. 1 and in full lines Fig. 9. This groove extends a substantial distance from the inclined edge 9 downward in the direction of the butt 10 and its purpose will hereinafter appear.

Cooperating with the yarn drawing member is a member 12 herein designated as a sheath, the principal function whereof is to enter the loop supported upon the shank of the knitting instrument and to spread or otherwise manipulate said loop so as to permit the yarn drawing member with its newly received yarn to be drawn therethrough for the purpose of forming a new loop, but during such operation it is desirable that the 95 spreading of the loop be reduced to a minimum so that the yarn comprising said loop will not be unduly stretched or its normal elasticity or strength be impaired and furthermore so that there will be as little rendering of 100 yarn from one loop to another as possible when knitting is being produced upon a series of the instruments.

To best accomplish the above results the sheath, or at least that portion of said sheath 105 that is used as a loop entering element, is arranged in slidable engagement with one side only of the yarn drawing or hooked member 2 and herein against that side containing the groove 11. The term "side" is 110

herein used to designate the faces of the members 2 lying parallel with the plane of the hook.

The sheath 12 may vary in length although preferably it extends substantially the length of the yarn drawing member 2 so as to provide a better support for the latter members particularly where the instrument is to be placed in grooves of a needle carrier 10 or cylinder.

It is not essential that the entire sheath be arranged at one side only of the member 2 although such an arrangement is preferable as it makes the total thickness of the 15 member 2 and the sheath 12 uniform throughout the length of the instrument hence providing lateral support for all parts thereof, the grooves in the needle cylinder being substantially equal in width to the 20 total thickness of said instrument.

As one function of said sheath is to enter the loop supported by the knitting instrument, it is desirable that the two members constituting said instrument be given from 25 time to time relative sliding movements and that during said sliding movements said members be properly guided one upon the other. For this purpose means are provided which herein consist of outstanding portions 30 or ribs 13 and 14 at the front and rear edges respectively of said sheath, which ribs engage the corresponding front and rear edges of the shank 8 of the yarn drawing member 2.

35 The rib 14 extends substantially the entire length of the sheath, but the front rib 13 terminates at a point 17 considerably above the butt 10 principally for the purpose of producing a gap 16 to expose the front edge 40 of the shank 8 whereby, when said instrument is used in a knitting machine, the usual spring bands may be employed to provide the necessary friction between the said instrument and the bottom of the groove in 45 said cylinder and also to retain said member 2 against the rear rib 14, the purpose of the latter function being hereinafter more fully explained.

50 The terminating of said rib 13 at the point indicated also provides a gap 18 through which the butt 10 of said yarn drawing member may protrude so as to permit action thereon by its functioning means. Below the range of movement of said butt the 55 rib 13 is supplemented by a filler block 19 which constitutes a guide for the lower end of the shank 8. Furthermore the block 19 is of considerable depth being substantially coextensive with the portion of the sheath 60 to which the block is attached; said coextensive portions extending to the face of the needle cylinder, thus to provide a continuous surface for engagement with the knitting cams of the machine.

65 The relative sliding movements of the

members 2 and 12 may be produced in various ways and it is not imperative that they be given positive independent movement. Herein, however, I have elected to provide the member 12 with an independent operating butt 15 constituting for convenience an extension of the filler block 19, and this butt 15 and the butt 10 of the yarn drawing member are adapted at the proper times to be acted upon and thus positively function 75 their respective members.

As previously stated one function of the sheath is to enter the old loop supported by the yarn drawing member and in order that said sheath may be made to enter such a 80 loop, the upper end thereof is reduced in size, preferably pointed at 20 herein by tapering or bevelling the end of said sheath at 21 and 22 on the front and rear portions thereof so as to position the apex or point 20 substantially midway of the front and rear edges of the sheath or at such a location that said point will lie between the neck 7 and the beard 4 of the hooked yarn drawing member. In addition to being pointed the upper end of said sheath is slightly inturned as shown most clearly in Figs. 7 and 8 and the inturned point so formed is arranged to move lengthwise in the hereinbefore described groove 11 of said yarn drawing member, during the knitting operations.

A second and very important function of the sheath 12 is to guard or cover the point 5 of the hook in order to effect the shedding of the old loop and in the present example this function is effected by forming upon said sheath, point guarding means as shown at 21' constituting a part of the outstanding flange 13 at the front edge of the sheath. The member 21' is separated from the body or the main portion of said flange by a recess 22' which is extended laterally of the sheath member slightly beyond the inner face of the outstanding portion 13 and constitutes a throat for said sheath wherein the old loop during the knitting operation may rest and be separated by the point guard 21' from the new yarn which is fed to the needle during the knitting operation when the hooked end of the yarn drawing member and the loop entering point 20 of said sheath are separated as shown in Fig. 4.

As clearly shown in Figs. 7 and 8 the point guarding member 21' is especially formed, or in other words all corners are rounded and the upper and lower edges 23 and 24 are sharply inclined so as to facilitate the riding of the loop or yarn over said member in either direction during the reciprocations of said sheath, said point guarding member being substantially the equivalent of the spoon employed in the ordinary latch knitting needle. It will be seen by referring to Fig. 9 that the guard 21' is slightly rounded or curved at 27 to effect a

substantial conformance of said guard with the rounded and tapered beard 4 of the hook 3 and also to provide a smooth and not too abrupt hump over which the old loop may ride when sufficient pressure is exerted thereon. It will also be evident that by curving said guard as shown the beard of the hook when covered or protected thereby will be less likely to become deflected or misplaced with respect to said guard by reason of the recess formed thereby and within which the point or beard of said hook will rest during the loop shedding operations.

In Figs. 2 to 6 inclusive the knitting instrument is shown in various positions indicating certain steps of the loop forming operation these positions being shown in relation to the knitting plane indicated by the line *a—a*. In Fig. 2 the two members namely the yarn drawing member 2 and the sheath 12 are indicated as occupying positions wherein the old loop has just been shed from the hook and the knitted web is shown supported upon the neck of said hook. Fig. 3 illustrates the two members of the knitting instrument separated so as to bring the inclined surface 9 of the yarn drawing member just above the corresponding inclined portion of the sheath 12 or in other words this inclined surface 9 on the hook member is arranged just above the lowermost point of travel of the loop entering element of the sheath 12 and cooperates therewith to perform the next or loop entering step in the operation. With the members in these positions they having previously been moved thereto by means of the butts 10 and 15, the instrument is in a position to be raised with respect to the line *a—a* so as to cause the loop entering point 20 to enter the loop shown supported by the shank of the needle, preferably at one side and substantially midway of the throat and the supported or closed end thereof. At this time said loop entering point is resting in the slot or groove 11 and by being inturned as described, said point will be buried beneath the edges 25 and 26 upon opposite sides of said groove (see Fig. 9) and thereby all danger of said point striking the side of said loop will be removed. As said knitting instrument continues to rise, the inclined surface 21 of the sheath will have a tendency to spread the loop and at the same time effect a progressive wiping action from the point of engagement thereof toward the supported end of the loop, or in the natural direction of elongation of said loop, and thereby tend to prevent elongation or strain of that portion of the loop that is so susceptible to such strains in the ordinary method of knitting namely that part which directly engages the front portion of the shank of the needle. The joint movement of the sheath and hooked yarn drawing member

upward continues until the loop supported by the shank of the yarn drawing member has reached the throat 22 of the sheath as shown in Fig. 4 which indicates this step in the operation and at this time a new yarn is laid across the neck of the hook beneath the beard thereof.

The next step in the knitting operation consists in relatively moving the members 2 and 12 until the point 5 of the beard is fully covered by the guard 21' but to insure said point passing inside of the guard 21' rather than outside, or rather than striking upon the upper edge of said guard, the engaging portions are relatively bevelled. For example the beard in the present instance is tapered upon its outer edge as previously described and should the beard accidentally or otherwise be bent slightly outward the abruptly inclined portion 6, by engaging the upper edge of said guard, will be deflected inwardly to its normal position within said guard.

To still further insure the passing of said point 5 inside of the guard 21' the rib 13 has been cut away as hereinbefore stated to form the gap 16 through which the spring bands of the knitting machine, not shown, may engage directly against the front edges of the shanks 8 of the yarn drawing members and cause them to remain pressed firmly against the rear rib 14.

Following the last mentioned operations the yarn drawing and sheath members are moved simultaneously to a lower position causing the loop that up to now has been resting in the throat below said guard to be released therefrom and shed or cast off over the hook and the yarn contained therein, thereby forming a new loop as will be seen in Fig. 6.

As a natural consequence of arranging the sheath member at one side only of the hooked yarn drawing member and in constructing said sheath of very thin material, little, if any, stretch will be produced in a loop during the insertion of the loop entering portion of said sheath and in the subsequent shedding of the said loop over the end of the hook.

Within the scope and purpose of the invention the instrument herein shown and described may be used either in crocheting or in knitting by hand, or said instrument is equally adapted for use in various types of knitting machines wherein the butts 10 and 15 will be functioned automatically by suitable knitting cams and for purposes of the present application the term knitting should be understood as including various constructions such as crocheting, knitting or the like.

While I have herein shown and described merely for illustrative purposes one specific embodiment of my invention and have dis-

closed and discussed in detail the construction and arrangement incidental to such disclosure, it is to be distinctly understood that the invention is limited neither to the mere 5 details or relative arrangement of the parts nor to the specific application herein shown, but that extensive variations from the illustrations may be made without departing from the principles thereof.

10 Claims:

1. A knitting instrument comprising a yarn drawing member and a sheath having a loop entering element arranged at one side of said yarn drawing member substantially midway between the edges of said sheath.

2. A knitting instrument comprising a yarn drawing member and a sheath having a loop entering element arranged at one 20 side only of said yarn drawing member intermediate the edges of said sheath.

3. A knitting instrument comprising relatively slidable hooked yarn drawing and sheath members, said sheath member having a pointed loop entering element located at 25 one side only of said yarn drawing member and between the neck and beard of the hook of said latter member.

4. A knitting instrument comprising a 30 yarn drawing member and a sheath having an inturned loop entering point arranged to move longitudinally and at one side of said yarn drawing member.

5. A knitting instrument comprising a 35 yarn drawing member grooved along one side below the neck thereof and a sheath having an inturned tapered loop entering element arranged with its apex substantially intermediate the front and rear edges of said 40 sheath to move in the groove of said yarn drawing member.

6. A knitting instrument comprising a grooved yarn drawing member and a sheath arranged at one side of said yarn drawing 45 member having guiding portions at the front and rear edges thereof, the end of said sheath being bevelled at its front and back edges to form a point for cooperating with the groove of said yarn drawing member 50 to enter a loop.

7. A knitting instrument comprising a grooved yarn drawing member, and a sheath arranged at one side of said yarn drawing member having outstanding guiding portions at the front and rear edges thereof, the end of said sheath being bevelled at its front and back edges to form a point for cooperating with said yarn drawing member to enter 55 a loop and means including a part of the outstanding portion at the front edge of said sheath to effect the shedding of a loop from said yarn drawing member.

8. A knitting instrument comprising a hooked yarn drawing member and a one-

sided sheath member having a loop entering 65 element arranged to enter the loops supported by said yarn drawing member at the side and intermediate the throat and the supported end of said loop.

9. A knitting instrument comprising a 70 hooked yarn drawing member and a sheath member having a loop entering element arranged to enter the loop supported by said yarn drawing member at one side only and intermediate the throat and the supported 75 end of said loop.

10. A knitting instrument comprising a hooked yarn drawing member having a groove extending longitudinally of one side of its stem, a sheath arranged to slide upon the grooved side of said hooked member and having an inturned loop entering element to move lengthwise in said groove and means on said hooked member to cooperate with said groove in effecting the entrance of said 80 element in a loop.

11. A knitting instrument comprising a hooked yarn drawing member having a groove extending longitudinally of one side of its stem, a sheath arranged to slide upon the grooved side of said hooked member and having an inturned loop entering element to move lengthwise in said groove and means including an inclined edge on said hooked 85 member to cooperate with said groove in effecting the entrance of said element into a loop.

12. A knitting instrument comprising a hooked yarn drawing member having a 100 groove extending longitudinally of one side of its stem, a sheath arranged to slide upon the grooved side of said hooked member and having an inturned loop entering element to move lengthwise in said groove and means including an inclined edge on said hooked 105 member adjacent to the lowermost point of travel of said loop entering element to cooperate with said element in effecting the entrance thereof into a loop.

13. A knitting instrument comprising a hooked yarn drawing member having a groove extending longitudinally of one side of its stem from the neck of said yarn drawing member downward, a sheath arranged 110 to slide upon the grooved side of said hooked member and having an inturned loop entering element to move lengthwise in said groove and means including an inclined edge on said hooked member above the lowermost 115 point of travel of said loop entering element to cooperate with said element in effecting the entrance thereof into a loop.

14. A knitting instrument comprising a hooked yarn drawing member, a sheath arranged to slide upon one side of said hooked member, a loop entering point formed upon said sheath at said side of said hooked member and intermediate its front 120 125

and rear edges and a hook point guard on said sheath to effect the shedding of a loop over the hook of said hooked member.

15. A knitting instrument comprising a hooked yarn drawing member, a sheath arranged to slide upon one side of said hooked member, a loop entering point formed upon said sheath intermediate its front and rear edges and a hook point guard at the front 10 edge of said sheath to effect the shedding of a loop over the hook of said hooked member.

16. A knitting instrument comprising a hooked yarn drawing member having a groove at one side thereof, a sheath arranged to slide upon the grooved side of said hooked member, an inturned loop entering element on said sheath to move in the groove of said hooked member during its loop entering operations and means at the front edge of said sheath to separate the new yarn from the old loop during the loop forming operation.

17. A knitting instrument comprising a hooked yarn drawing member having a groove at one side thereof, a sheath arranged to slide upon the grooved side of said hooked member, an inturned loop entering element on said sheath to move in the groove of said hooked member during its loop entering operations and means extending from said sheath across the front edge of said yarn drawing member to separate the new yarn from the old loop during the loop forming operation.

18. A knitting instrument comprising a hooked yarn drawing member having a groove at one side thereof, a sheath arranged to slide upon the grooved side of said hooked member, an inturned loop entering element on said sheath to move in the groove of said hooked member during its loop entering operations and means extending from said sheath across the front edge of said yarn drawing member to separate the new yarn from the old loop during the loop forming operation and to cover the hook of said yarn drawing member to effect the shedding of said old loop.

50 19. A knitting instrument comprising a hooked yarn drawing member having a groove at one side thereof, a sheath arranged to slide upon the grooved side of said hooked member, a loop entering element formed at the end of said sheath to move in said groove during the loop entering operations, and outstanding guide members at opposite sides of said sheath to extend across the front and rear edges of said hooked 55 member, a portion of the front outstanding guide member being separated from the main portion thereof by a recess constitut-

ing a throat to receive the old loop supported by said instrument and to separate said loop from the new yarn during the loop forming operation.

20. A knitting instrument comprising a hooked yarn drawing member having a groove at one side thereof, a sheath arranged to slide upon the grooved side of 70 said hooked member, a loop entering element formed at the end of said sheath to move in said groove during the loop entering operations, and outstanding guide members at opposite sides of said sheath to extend across 75 the front and rear edges of said hooked member, a portion of the front outstanding guide member being separate from the main portion thereof by a recess constituting a throat to receive the old loop supported by 80 said instrument and to separate said loop from the new yarn during the loop forming operation, said separated portion also constituting a guard to cover the point of the hook of said yarn drawing member during 85 the loop shedding operation.

21. A knitting instrument comprising the yarn drawing member 2 having a hook 3, and the sheath member 12 provided with the loop entering element 20 arranged to 90 first enter the loop at a point at the side between the neck and beard of the hook.

22. In a knitting instrument the grooved hook member 2 and the relatively movable sheath member 3 having a loop entering element 20 adapted to first enter the loop at the side of said hooked member to move in said groove and a point guard 21' at the front of said hook member.

23. In a knitting instrument the hooked 100 yarn drawing member 2 and the pointed loop entering element 20 arranged to effect the initial loop entering function at one side of the hooked member between the neck and beard thereof.

105 24. A knitting instrument comprising a hooked yarn drawing member and a sheath member relatively slidably longitudinally of said yarn drawing member adapted to effect the initial entering of the loop at one side only of said hooked yarn drawing member.

25. A knitting instrument comprising a hooked yarn drawing member and a pointed sheath member relatively slidably longitudinally of and upon said yarn drawing member having its point adapted to effect the initial entering of the loop upon said 115 yarn drawing member at one side only of said loop.

In testimony whereof, I have signed my name to this specification.

SYDNEY E. TAFT.
